UNITED STATES PATENT OFFICE.

HARRY A. FOSTER, OF BRADENTON, FLORIDA.

STERILIZING APPARATUS.

Application filed October 8, 1926. Serial No. 140,374.

This invention relates to an improved sterilizing apparatus which is especially, but not necessarily, adapted for use by dentists for thoroughly cleansing their instruments, 5 hand-pieces, et cetera.

Briefly, the invention embodies a unitary structure composed principally of three major parts; namely, a special cabinet for the instrument drawer, a superposed horizontally disposed sterilizer for a hand-piece and an intervening horizontally disposed electrical means constituting a heater for an antiseptic solution which is used in association with the device.

15 The invention is characterized by such advantages as compactness and convenience of arrangement of parts, rapidity in handling and use, and practical application of sanitary science.

20 The more specific features of construction and advantages derived from their use will become apparent from the following description and drawings.

In the drawing:

25 Figure 1 is a front elevation of the complete apparatus,

Fig. 2 is a side view of the same,

Fig. 3 is a vertical section through the lower cabinet,

30 Fig. 4 is a longitudinal section through the hand-piece sterilizer, and

Fig. 5 is a section through the electrical heating device.

As before stated, the apparatus comprises 35 three main parts, the cabinet designated by the reference character 1, the horizontal sterilizer by the reference character 2, and the electrical heating device or coil by the reference character 3. Each part will be considered in detail.

40 Directing attention first to Fig. 3, it will be seen that the cabinet comprises a box-like casing 4 of metal, the same being open at its top and a removable cover 5 being provided for said open top. At the bottom and on the interior is a horizontal partition 6 dividing the casing into upper and lower compartments. In the lower compartment and supported on the under side of the partition 6 is an electrical heater 7 of suitable construction. 45 Disposed in the upper compartment near the top are supporting ledges 8 upon which the instrument drawer 9 is slidably supported. It will be noted in Fig. 1 that the face plate 50 of the drawer bears against the outer front wall of the cabinet and suitable packing ma-

terial is interposed between these parts to provide a fluid-tight joint. In this connection it might be stated that the drawer is provided with an external knob 10, and a thermometer 11. That portion of the compartment beneath the drawer forms a water and steam chamber. The normal water line is represented at 12 and means is provided for automatically maintaining the water at this 60 normal level, the means comprising a water supply pipe 13 having a valve casing 14 at its top and a valve 15 located therein. Connected to the valve through the medium of linkage and a supporting bracket 16 is a float-carrying arm 17 on which the float 18 is mounted. Connected to the right hand end of the float are two special links 19 and 20, one being hinged to the float and the other being hinged 65 to the wall of the casing, both of these links having curved portions pivotally connected together as at 21. Closely related to the mechanism just described is a blow-off valve 22 on the upper end of a pipe 23, which is connected with the water compartment below the level 70 of the water. In this pipe is a control valve 24.

Attention is now to be temporarily confined to Fig. 4 wherein the details of the sterilizer 2 are shown more plainly. This part comprises a cylindrical horizontally disposed body including three detachably connected sections 25, 26, and 27 respectively. The parts 25 and 26 are provided with partition walls 28 and 29, thus forming three chambers 30, 31 and 32. The chamber 32 is adapted to accommodate air under pressure from a suitable source of supply (not shown). The chamber 31 is adapted to contain and act as a reservoir for an antiseptic solution, while the chamber 30 constitutes a mixing chamber for the solution, spray and steam. Connected to the end wall of the air chamber is the supply pipe 33 which cooperates with a compressed air conducting pipe 34 leading into the antiseptic chamber 31 and also into a cylinder 34^a which is located in said chamber. This chamber 31 is provided with a suitable filler neck 35 and a closing cap 36. The partition 28 carries suitable fittings 37 and 38 which serve to connect the cylinder 34^a thereto. Located in this cylinder is a plunger 39 cooperating with the coil spring 40. This plunger includes a valve seat and a spray nozzle 41, the nozzle projecting through and beyond the fitting 37 and having a flat apertured end. It will be noted that a substantially L-shaped pipe is as-

sociated with each part, the same including a depending branch 42 extending down into the antiseptic fluid in the reservoir and a horizontal branch 43 extending through an opening in the plunger and terminating in a valve head 44. This valve head cooperates with the adjacent valve seat in the manner clearly obvious from the drawings.

A conventional form of hand-piece is generally designated by the reference character 45. Among other parts, this device includes the burr-holder 46, flexible drive 47, sleeve 48 and surrounding flanged collars 49 and 50, these being connected together in the relationship shown at the left-hand end of Fig. 4. In this connection I would state that the adjacent end of the section 25 is constructed to provide means for permitting the hand piece to be inserted into the chamber 30 to subject it to the action of the antiseptic spray. The means comprises a guide composed of parts 51 and 52. This guide is stationary, and relatively movable means is associated therewith. The means comprises a bushing 53 and a detachably connected annulus 54 including suitable packing means. The annulus includes a flange which projects beyond the part 51 of the guide and this serves as a mounting for a pair of special finger latches 55. These latches are constructed to provide seats for the forefingers and include hook-shaped portions cooperating with keepers on the collar 49 for maintaining the latches in holding position. It will be noted that spring means is associated with the slideable part so that it may move inwardly a limited distance. If desired, the air compartment 32 may be provided with a gauge 56.

Attention is now again directed to the electrical contrivance 3 represented in Fig. 5. As here shown the same comprises an elongated cylindrical casing 57 having a core 58 carrying electrical heating elements 59 supplied from a conductor 60.

As shown in the assembled Figs. 1 and 2, the sterilizer 2 is supported on appropriate legs 61 which are connected to the removable cover for the cabinet 4. An appropriate connection 62 is provided for hanging the part 3 from the under side of the part 2. A pipe connection 63 is bowed between parts 2 and 3 and a control valve 64 is provided therefor. In addition, a pipe connection 65 is had between the other end of the part 3 and the aforesaid cabinet 1.

It will be understood from the foregoing that when the water in the cabinet is boiled under the action of the electrical heating means 7, it will be converted into steam for steaming and cleaning the instruments in the instrument drawer 9. Obviously, when the steam assumes an excessive or abnormal pressure, it may blow off or through the blow-off device 22 after the valve 24 is opened. Moreover, when the water goes below a pre-

determined level, the automatic float device comes into play and opens the water supply, allowing replenishment. This avoids the danger of destroying the apparatus such as frequently occurs when all of the water has boiled out. In using the part 2 of the device, the hand-piece, which is of conventional form, is inserted through the guide and retaining device explained in detail and the latches are hooked in place to hold it in position. Then the spring-pressed movable part of the retainer is forced inwardly by manual pressure to bring the part 46 into engagement with the perforated end of the nozzle 41. In so doing, the plunger 39 is forced inwardly against the action of the spring to unseat the valve 44, thus permitting the air under pressure to pass from the compartment 32, through the pipe 34 and into the cylinder 34a. The air under pressure rushes in between the branch 43 and the opening around the same and passes beyond the valve 44, and also around the plungers, valve 39 and thence through the opening of the primary mixing chamber creating a suction, which draws the antiseptic solution in the chamber 31 with it, thus producing a spray which is ejected through the nozzle 41 and onto the parts 46 of the hand-piece. On the withdrawal of the hand-piece the valve closes and the action just explained ceases. A part or a portion of the spray now drains downwardly through the valved pipe 63 and is subjected to heat in the electrical heating device 57, and passes on further through the pipe 65 and drips into the aseptic drawer in the aforesaid sterilizing cabinet, thus subjecting the instruments in the drawer to a constant antiseptic drenching. It is also obvious that by opening the valve 64 in the pipe 63, steam rising from the cabinet may be allowed to pass through the electrical device 57 into the mixing chamber 30. This action both cleanses and dries off accumulations of germs and bacteria. Thus, the hand-piece not only receives the antiseptic bath, but is subjected to a mechanical impact of the antiseptic spray which has such force as to absolutely remove all bacteria from the crevices in the metal.

By suspending the device on an appropriate bracket, it will be always in position so that the dentist may simply turn half-around, insert the hand-piece and clean it in a few seconds. Also, after each operation, the instruments may be placed in the drawer and the drawer pushed in to be subjected to the cleaning operation.

By considering the detailed description in connection with the illustration shown in the drawing, a clear understanding of the construction and operation of the invention will be obtained. Many advantages other than those specifically referred to will become apparent to those skilled in the art to which the invention relates. In view of this, a more

lengthly description is thought unnecessary.

While the preferred embodiment of the invention has been shown, it is to be understood that minor changes coming within the field 5 of invention claimed may be resorted to if desired.

I claim:

1. In a structure of the class described in combination, an instrument cleansing cabinet including an instrument drawer, and a superposed device carried thereby and constructed for subjecting a dental hand-piece to the sterilizing action of an antiseptic spray, and means interposed between the antiseptic device and the cabinet for conducting a portion of the antiseptic solution from said device into said cabinet, where it is deposited in said instrument drawer.

2. In a sterilizing device of the class described, a casing divided into a compressed air chamber, an antiseptic solution chamber, and a mixing and spray-receiving chamber, the last named chamber being constructed for introduction of a part of a dental hand-piece 25 to be sterilized, means affording communication between the air chamber and the solution chamber, and a valve-controlled device associated with the solution chamber and adapted

to be rendered operative by the pressure of the hand-piece against said device.

3. In a sterilizing apparatus of the class described, a casing composed of three separably connected sections which when connected together provide closed ends and centrally spaced partitions, dividing the casing into three independent compartments, one compartment forming an air pressure chamber, the next compartment forming an antiseptic solution container and the remaining compartment forming a mixing and spray chamber, a compressed air pipe connected with said air chamber, a cylinder supported in said solution chamber, a communicating pipe connection between the cylinder and said air chamber, a solution conducting and delivery pipe associated with said cylinder, a plunger slidable in said cylinder and cooperable with the solution pipe for controlling the supply of air through the cylinder, said plunger including a spray nozzle located in 45 said mixing chamber, and a guide and retaining device for a hand-piece carried by the end wall of said mixing chamber.

In testimony whereof I affix my signature.

HARRY A. FOSTER.
